THOMAS BELL, OF NEW YORK, N. Y.

Letters Patent No. 71,686, dated December 3, 1867.

IMPROVEMENT IN INK-WELLS.

The Schedule referred to in these Letters Patent and making part of the same.

TO ALL WHOM IT MAY CONCERN:

Be it known that I, THOMAS BELL, of New York, corner of One Hundred and Twenty-Fifth street and Fourth avenue, in the county of New York, and in the State of New York, have invented a new and useful Improvement in Ink-Wells and Covers; and I do hereby declare the following to be a full, clear, and exact description thereof, which will enable those skilled in the art to make and use the same, reference being had to the accompanying drawing, forming part of this invention, in which drawing—

Figure 1 represents a transverse section of an ink-well constructed according to my invention, when the same is closed.

Figure 2 is a similar section of the same when open.

Figure 3 is a section of a modification thereof, showing the ink-well closed.

Figure 4 is a similar view of the same when the ink-well is open.

Similar letters indicate corresponding parts.

This invention relates to an improvement in ink-wells with sliding covers, and it consists in providing either the under surface of the cover, or that portion of the table or desk on which the cover slides, when being opened, with a projection or ridge, in such a manner that in opening the cover the inner surface of the same is thrown off from the surface of the table or desk, and that portion of said table or desk next to the ink-well is preserved from being soiled by ink adhering to the under surface of the covers.

A represents an ink-well, which is inserted into the desk or table B in the ordinary manner. Said ink-well is provided with a sliding cover, C, which swings on a pivot, a, and which may be made of cast iron or any other suitable material.

In ink-wells with sliding covers of the ordinary construction, the ink is liable to adhere to the inner or under surfaces of the covers, and in opening the covers that portion of the desk or table adjoining the ink-wells is liable to become soiled, and the ink thus transferred to the table or desk adheres to the fingers or hands of the persons dipping their pens in the ink-wells.

On account of this difficulty, ink-wells with sliding covers have been abandoned, particularly in schools, and hinged covers have been substituted. But hinged covers are liable to be knocked off, if pushed against when open, by a slate or book, and for this reason a sliding cover will be preferred in most schools, provided it can be made so that it will not soil the surface of the table or desk.

This desideratum I have effected either by applying to the under surface of the cover a projection, b, as shown in figs. 1 and 2, or by providing the surface of the table or desk with a projection or ridge, c, as shown in figs. 3 and 4. In either case, if the cover is opened, the projection b or ridge c throws the under surface of the cover off from the surface of the table or desk, and the ink which may adhere to the inner surface of the cover is not liable to be transferred to the table or desk.

What I claim as new, and desire to secure by Letters Patent, is—

The arrangement of a projection or ridge either on the under surface of a sliding ink-well cover or on that part of the ink-well table or desk over which the cover passes when being opened, substantially as and for the purpose described.

THOS. BELL.
